UNITED STATES PATENT OFFICE.

MARK BARR, OF BROADHEATH, ENGLAND, ASSIGNOR TO THE LINOTYPE COMPANY, LIMITED, OF LONDON, ENGLAND.

ENGRAVING-MACHINE.

SPECIFICATION forming part of Letters Patent No. 761,349, dated May 31, 1904.

Application filed September 28, 1899. Serial No. 731,928. (No model.)

To all whom it may concern:

Be it known that I, MARK BARR, of Broadheath, in the county of Chester, England, have invented certain new and useful Improvements 5 in Engraving-Machines; and I do hereby declare the following to be a full, clear, and exact description of the invention, such as will enable others skilled in the art to which it appertains to make and use the same.

10 The present invention relates to improvements in pantograph engraving-machines the tracer-rod and tool of which are constantly vertical. In carrying it into effect the tracer is made capable of a reciprocating vertical motion, and a like vertical motion at the work end of the machine is provided for, of which either the tool or the work-table is capable, both such motions being provided by the improved means hereinafter described and illustrated. 15 The term "work end" of the machine is used to indicate that end of it where the tool and work coöperate. This coöperation is as heretofore. It is immaterial for the purpose thereof whether the tool moves over the work or whether the work is moved past the tool.

The means by which the above-mentioned like vertical motion at the working end of the machine is secured may for the purpose of 20 the present invention be applied to either the tool or to the work. The horizontal motion of the tracer is guided by a special guide consisting of a horizontal guide-plate to which it is made fast, and which plate is capable of a 25 horizontal motion in a horizontal guide in any direction, the length of any such motion being limited only by the size of the horizontal guide. Whichever of the two—tool or work-table—has not the capacity for reciprocating vertical motion has a horizontal motion 30 in any direction, thus constituting it the horizontally-moving member at the work end of the machine. Such horizontal motion is likewise guided by a similar special guide. 35 The pantograph is connected to the tracer and to the horizontally-moving member at the work end of the machine. The reciprocating vertical motion of the tracer is transmitted in the proper proportion to the tool through a

lever which has its fulcrum adjustable for ratio 50 between the respective depths of the pattern and work and is pivotally connected to both tracer and tool. It is also adapted, by means of telescopic joints, to automatically compensate for variations in its length. 55

Referring to the accompanying drawings, which are to be taken as part of this specification and read therewith, Figure 1 is a side elevation illustrating the invention constructed with stationary work-table; Fig. 2, a plan 60 corresponding therewith, and Fig. 3 a side elevation illustrating the invention constructed with a horizontally-moving work-table.

Referring first to Figs. 1 and 2, 1 is the base; 2, the pattern; 3, an elevated part thereon; 4, a standard held to the base 1 by screws 5 screwed down thereinto through a flange 7; 8 8, a pair of parallel arms standing out horizontally from the top of the standard 4 in the direction of the work end of the machine to 70 carry posts 9 9, whose function is to act as a fixed guide for the vertical motion of the guide 10 of the horizontal guide-plate 12. The arms 8 8 stand apart from each other far enough to allow of the horizontal motion of 75 the tracer 13. This guide 10 is guided in its said motion by the four posts 9 by means of that number of lugs 11, projecting diagonally from each of its corners and perforated to pass over the said posts and to slide freely up 80 and down them. The height of the posts 9 9 must be sufficient to allow of the maximum vertical motion of the tracer. The horizontal guide-plate 12 is capable of a horizontal motion in any direction. 85

13 is the tracer. It is made fast centrally to the under side of the guide-plate 12, from which it depends vertically between the arms 8 8.

Passing now to the work end of the machine, 90 14 is the work-table, 15 the work held down upon it by any suitable means, and 16 a projection upon it corresponding, respectively, with the pattern 2 and the projection 3.

17 is a standard fixed to the base 1 by flange 95 18 and screws 19 in the same way as the standard 4, already described.

20 20 are a pair of parallel arms standing

out horizontally from the top of the standard 17 in the direction of the tracer and pattern to carry four posts 21, whose function is to act as a fixed guide for the vertical motion of the guide 22 of the horizontal guide-plate 23 of the tool. The arms 20 20 stand apart from each other far enough to allow of the lateral motion of the tool. This guide 22 is guided in its said motion by the four posts 21 by means of as many lugs 24, projecting diagonally from each of its corners and perforated to pass over them, respectively, and to slide freely up and down them. The height of the posts 21 must be sufficient to allow of the maximum vertical motion of the tool.

23 is the horizontal guide-plate of the tool. It is capable of a horizontal motion in any direction proportionate to the motion of the tracer in the same direction.

25 is the tool-post.

26 is the tool carried by the bottom end of the post 25 and capable of rotation therein about an axis common to them both by means of a driving-band passed around the pulley 27, fast to the tool. This combination of tool-post 25, tool 26, driving-pulley 27, and band is of the usual description. Both guides 10 and 22 have openings 28 in them of corresponding areas to allow of the horizontal motions of the tracer 13 and the tool-post 25, respectively.

30 is the lever connecting the two guide-plates 10 and 22, and 31 is its fulcrum. It is connected to the guide 10 of the tracer 13 by a pivot-joint 32, having a horizontal axis on the top of a post 33, standing up from the center of the top of the said guide 10, to which it is made fast, and to the guide 22 by a similar pivot-joint 34 on the top of a post 35, standing up from the center of the top of the said guide 22. The fulcrum 31 is a universal joint on the top of a post 36. This fulcrum 31 is fixed for any given length of the lever 30 between it and the pivot 32; but it is adjustable horizontally for ratio between the respective depths of the pattern and the work in the direction of its own length along a guiding-groove 37 in a bracket 38, projecting from the standard 17.

39 is a scale on the top of the bracket 38 to guide the operator in adjusting the position of the fulcrum 31, and 44 is a set-screw for holding the fulcrum in its adjusted position. To allow of the variations in the height of the fulcrum 31 above the bracket 38, due to the varying position of the fulcrum 31 along the said bracket, the post 36 is adjustable vertically in a socket 40, in which it can be fixed at any height by a set-screw 41. It is therefore the socket 40, acting as the foot of the post 36, that engages directly in the groove 37.

42 is a telescopic joint in the length of the lever 30 between the fulcrum 31 and the pivot-joint 34, and 43 is a second one between the said pivot-joint 34 and the pivot-joint 32

to compensate for the variations in the length of the lever 30 which will occur with the reciprocating vertical motion of the two pivot-joints 34 and 32.

45 is a pantograph connecting the tracer 13 and the tool-post 25. Any suitable type of pantograph may be used. The invention imposes no limit in that respect. It requires only that the pantograph connect the tracer and the horizontally-moving member at the work end of the machine—the tool in the construction being described—to each other directly.

The action of the invention constructed as above described is as follows: The pantograph 45 is first adjusted and then the position of the fulcrum 31, both for the desired ratio between the pattern 2 and the work 15. So long as the tracer 13 has only to move over the pattern 2 in the horizontal plane its motion is communicated, through the pantograph 45, to the tool-post 25, the motions of both tracer 13 and tool-post being steadied by the respective guide-plates 12 and 23, and the lever 30 automatically shortening and lengthening itself accordingly, as the pivot-joints 32 and 34 reciprocate vertically; but when the contour of the pattern 2 requires the point of the tracer 13 to rise, as would be the case when it came to deal with a projection, such as 3, the guide-plate 12 pushes the guide 10 up the guide-posts 9, carrying the pivot-joint 32 vertically upward with it. The fulcrum 31 of the lever 30 being held against vertical motion by its connection to the bracket 38, the arcual motion of the lever 30 upward pulls the pivot-joint 34 upward for a corresponding distance, according to the ratio between pattern and work established by the above-described adjustment of the pantograph 45 and lever 30. The upward motion of the pivot-joint 34 must be vertical because of the engagement of the posts 21 in the lugs 24 and is shared by the tool 26. When the point of the tracer 13 is dealing with the horizontal top of the projection 3, the machine works as with any other horizontal surface. When it has to descend one of the sides of the said projection 3, the two guides 10 and 12 are moved vertically downward, the former by the descent of the tracer 13 and the latter by the descent of the lever 30. The pantograph 45 always moves up and down with the tracer 13 and the tool-post 25.

The projection 3 is shown as rectangular in cross-section to the better illustrate the sequence of horizontal and vertical motions on the part of the tracer and tool and of the connecting members of the machine. In actual practice the contours will be convex and concave; but as any curved line is under the circumstances of engraving a certain compound of vertical and horizontal components the motions of the tracer 13 and the tool-post 25 will each be a similar compound, the pantograph

45 and the lever 30 sharing those components between them and compounding them in the motion of the tool 26.

In the construction illustrated in Fig. 3 the invention remains exactly the same as in the construction just described. There are the same functions and the same means for enabling the machine to discharge them, the only difference being the transference of the tool's capacity for lateral motion to the work-table. For that reason those organs in Fig. 3, which are the counterparts in all respects of organs in Figs. 1 and 2, are marked with the same reference and need no further description, while those which are affected by the difference above mentioned are marked with the same references with a superior "a" added.

14" is the work-table; 22", the guide for the guide-plate 23"; 50, a vertical post holding the said guide-plate and work-table fast together, and 28" the opening to allow of the horizontal motion of the said post. The respective organ of the pantograph 45 is connected to the post 50 to move the work-table 14". The tool-post 25" has a vertical motion in a single central arm 20", which serves as its guide. Thus the horizontal motions of the tracer 13 are transmitted by the pantograph 45 to the work end of the machine in exactly the same way and with the same effect on the combination of tool 26 and work 15 as in Figs. 1 and 2.

I claim—

1. The combination in an engraving-machine, of horizontally-moving member at the work end of the machine; pantograph connecting the tracer with the said member; tracer capable of vertical motion; tool capable of vertical motion; fixed guides adapted to direct the vertical motions of the tracer and tool re-

spectively; special guide for the horizontal motion of the tracer, consisting of a horizontal guide-plate to which the said tracer is made fast, and a guide in which the guide-plate is capable of horizontal motion in any direction; a like special guide for the horizontal motion of the horizontally-moving member at the work end of the machine; and lever having a fulcrum adjustable for ratio between the depths of the pattern and the work, telescopic joints in its length to compensate for variations therein, and pivotal connections to the tracer and to the vertically-moving member at the work end of the machine.

2. The combination in an engraving-machine, of pantograph connecting the tracer with the tool; tracer capable of vertical motion; tool capable of vertical motion; fixed guides adapted to direct the vertical motions of the tracer and tool respectively; special guide for the horizontal motion of the tracer, consisting of horizontal guide-plate to which the said tracer is made fast, and a guide in which the guide-plate is capable of horizontal motion in any direction; a like special guide for the horizontal motion of the tool; and lever having a fulcrum adjustable for ratio between the depths of the pattern and the work, telescopic joints in its length to compensate for variations therein and pivotal connections to the tracer and to the tool.

In testimony that I claim the foregoing as my invention I have signed my name in presence of two subscribing witnesses.

MARK BARR.
